Primary Examiner — Paul D Bohannon

(57) **CLAIM**

The ornamental design for a recreational game chair, as shown and described.

DESCRIPTION

FIG. 1 is a top front right perspective view of a recreational game chair showing my new design;

FIG. 2 is a bottom front left perspective view thereof;

FIG. 3 is a top rear left perspective view thereof;

FIG. 4 is a bottom rear right perspective view thereof;

FIG. 5 is a front elevational view thereof;

FIG. 6 is a rear elevational view thereof;

FIG. 7 is a right elevational view thereof;

FIG. 8 is a left elevational view thereof;

FIG. 9 is a top plan view thereof; and,

FIG. 10 is a bottom plan view thereof.

The broken line showing netting, a bag feature, and a bag strap in FIG. 1-10 is included for the purpose of illustrating environmental structure and forms no part of the claimed design.

1 Claim, 10 Drawing Sheets
